UNITED STATES PATENT OFFICE

HOMER G. KELLOGG, OF DETROIT, MICHIGAN, ASSIGNOR TO MOTOR PRODUCTS CORPORATION, OF DETROIT, MICHIGAN, A CORPORATION OF NEW YORK

DESIGN FOR A HOOD HINGE

Application filed May 5, 1930. Serial No. 35,498. Term of patent 14 years.

To all whom it may concern:

Be it known that I, HOMER G. KELLOGG, a citizen of the United States of America, residing at Detroit, in the county of Wayne and State of Michigan, have invented a new, original, and ornamental Design for Hood Hinge, of which the following is a specification, reference being had therein to the accompanying drawings forming a part thereof, in which Figure 1 is a perspective view of a hood hinge constructed in accordance with my new design; and Figure 2 is a perspective view of the hinge.

The dominant feature of my new hood hinge is the taper of the hinge from the radiator end to the cowl end together with the oppositely extending inclinations which begin at the longitudinal medial line of the hinge and extend oppositely therefrom toward the longitudinal edges of the hinge.

I claim:

The ornamental design for a hood hinge substantially as shown, and described.

HOMER G. KELLOGG.
